UNITED STATES PATENT OFFICE.

SAMUEL L. KISTLER, OF LOS ANGELES, AND HENRY SYMONDS, OF LONGBEACH, CALIFORNIA, ASSIGNORS TO SUPERIOR LIGHT AND HEAT CO., OF LOS ANGELES, CALIFORNIA, A CORPORATION OF CALIFORNIA.

ACETYLENE-GAS BURNER.

SPECIFICATION forming part of Letters Patent No. 784,687, dated March 14, 1905.

Application filed September 16, 1904. Serial No. 224,768.

To all whom it may concern:

Be it known that we, SAMUEL L. KISTLER, residing at Los Angeles, and HENRY SYMONDS, residing at Longbeach, in the county of Los Angeles and State of California, citizens of the United States, have invented new and useful Improvements in Acetylene-Gas Burners, of which the following is a specification.

Our invention relates to a burner more especially designed to produce heat than light; and the object thereof is to produce an acetylene-gas burner of simple construction that will produce a large amount of heat. We accomplish this object by the burner described herein and illustrated in the accompanying drawings, in which—

Figure 1 is a vertical central section of one of the burner-tips and a cross-section of a portion of the supply-chamber. Fig. 2 is a plan view of the supply-chamber and burner-tips.

In the drawings, 1 is the usual mixing-tube, provided with the usual air-inlet and spud, which supplies the gas to the burner, these latter elements not being shown. The mixing-tube opens into the annular supply-chamber 2, which is preferably semicircular in cross-section, as shown in Fig. 1. The casing of this chamber is preferably cast in two parts, which are secured together by bolts 3, the top plate 4 being an annular plate provided with burner-tips 5, of which there may be any desired number. These burner-tips consist of a series of circular chambers 6, 7, 8, and 9 of different diameters, which we have found by experiment produce the best result when made about the proportion shown in Fig. 1, the diameter of the upper section 6 being ten thirty-seconds of an inch, that of section 7 being eleven thirty-seconds of an inch, that of section 8 being twenty-three sixty-fourths of an inch, and the largest diameter of section 9 being nine-sixteenths of an inch, and the total height of the tip being five-eighths of an inch from the bottom of chamber 8 to the top of chamber 6. The top wall of chamber 6 we have found should be one thirty-second of an inch thick and should be slightly globular, as shown

in Fig. 1, and the gas-orifice 11, leading therefrom, is formed by cutting through the top, in the center thereof, to the vertical wall with 50 a fine hack-saw. Across the bottom of chamber 9 is a fine wire-gauze screen, which is held in place by having the edges thereof placed between the upper and lower sections of the supply-chamber.

Fig. 1 shows the proper proportion of a burner-tip which we have found by practice to produce the most satisfactory results of any burner-tip that we have tried in our experiments, of which we have made a great many, 60 and is drawn to a scale which is four times as large as the actual size of the tip which we have used. We have found by our experiments that the proportions may be varied within reasonable limits, but that the above 65 proportions produce the best results. A burner thus constructed provides a simple and efficient heat-producing acetylene-gas burner that will produce a wide flat blaze and will produce more heat units than any other form 70 of burner that we were able to construct during our experiments or that we have ever seen used for that purpose. The successive enlargements of the chambers of the burner-tips, as shown in Fig. 1, permit of the full 75 force of gas-pressure to pass out of the gas-orifice at the top, which orifice being very narrow prevents back firing.

By using a sufficient number of tips with the orifice on a line substantially parallel with 80 the outside of the supply-chamber and placing them sufficiently close together, as shown in Fig. 2, the flame produced by the various tips impinge, thereby making a substantially circular flame, which is a great improvement 85 over those burner-tips which have unobstructed outlets, thereby producing detached jets of flame.

Having described our invention, what we claim as new, and desire to secure by Letters 90 Patent, is—

1. In an acetylene-gas burner for producing heat, a burner-tip consisting of a plurality of circular chambers of increasing diameter from

the top toward the bottom, the top chamber having a narrow slitted orifice, extending from one side wall to the other and passing centrally across the top of said chamber through 5 the top plate thereof.

2. An acetylene-gas burner comprising a mixing-tube, a supply-chamber into which said mixing-tube opens, burner-tips connected and opening into said supply-chamber, said burner-tips having narrow slitted outlets, and being composed of a plurality of circular chambers of increasing diameters toward the bottom. 10

3. An acetylene-gas burner comprising a mixing-tube, a supply-chamber into which said 15 mixing-tube opens, burner-tips connected and opening into said supply-chamber, said burner-tips having narrow slitted outlets, and being composed of a plurality of circular chambers of increasing diameters toward the bottom,

wire screening intermediate said burner-tips 20 and supply-chamber.

4. An acetylene-gas burner comprising a mixing-tube, an annular supply-chamber into which said mixing-tube opens, burner-tips connected and opening into said supply-chamber, 25 said burner-tips having narrow slitted outlets, and being composed of a plurality of circular chambers of increasing diameters toward the bottom, wire screening intermediate said burner-tips and supply-chamber. 30

In witness that we claim the foregoing we have hereunto subscribed our names this 8th day of September, 1904.

SAMUEL L. KISTLER.
HENRY SYMONDS.
